UNITED STATES PATENT OFFICE.

CLAUDE A. WITTER, OF PHILADELPHIA, PENNSYLVANIA.

VULCANIZING MOLD.

Application filed December 24, 1925. Serial No. 77,437.

This invention relates to the molds used in vulcanizing automobile tires.

In general, these molds consist of two complementary half-ring members, which, when assembled, provide a mold cavity, the open face of which is closed by what is called a bull ring. These molds, with the tire to be vulcanized in position therein, are placed in containers, and subjected to heat, as by the application of steam, to vulcanize the rubber. There are two (2) kinds of containers ordinarily employed, one, the watch case type, which holds a single mold, and the other a much larger casing which holds a multiplicity of assembled molds.

It is an object of the invention to provide an improved mold which may be used in either of the two kinds of vulcanizers employed, and by virtue of which the capacity of these vulcanizers can be greatly increased.

Stated in another way, it is an object of my invention to provide an improved mold by virtue of which more tires can be vulcanized in a given space than heretofore.

Other and more specific objects will appear hereinafter in the description of the invention.

How the foregoing is obtained is illustrated in preferred form in the accompanying drawings, wherein—

Fig. 1 is a fragmentary view illustrating my improved mold partly in section, and

Fig. 2 is a cross sectional view illustrating a modification of the invention.

In carrying out my invention, I provide two mold cavities with three half rings, in contradistinction to one mold cavity with two half rings. To this end I provide two outer half rings 7 and 8, these rings being right and left hand members, but otherwise the same.

Between these half rings I locate the intermediate or third ring 9, which is complementary to the half rings 7 and 8, and cooperates with each to provide the two mold cavities 10 and 11. Each ring 7 and 8 is provided with a clamping lug, flange, or extension 12, and the intermediate ring 9 is also provided with such a portion 13. The clamping means is not shown, as this constitutes a well known expedient in this art. Any suitable form of clamping means can be used.

The one-half ring members 7 and 8 are each provided with an annular flange or rib 14, and the intermediate ring 9, on its two op-

posite faces, has a complementary hanging or flange 15, in consequence of which, when the three parts are clamped together, they align themselves into a rigid structure.

The inner peripheral portions of the three rings are shaped to receive the bull rings 16 indicated in light lines, these being the bull rings previously described as closing the open face of the molds.

It will be understood that the inner contour of the rings will vary, according to the contour of the particular tire to be vulcanized.

In utilizing this mold in the watch case type of vulcanizer, the molds will be inserted in the vulcanizer in a vertical position, and the steam will be supplied to the vulcanizer 70 in the usual manner. From what has been said, and from inspection of the drawing, it will be seen that the thickness of the completed mold for vulcanizing two tires is much less than would be required if the usual practice were followed. By the same token, more molds can be vulcanized in existing vulcanizers of the other type.

When utilizing the mold in the watch case type of vulcanizer, it will be desirable to provide special means for additionally heating the intermediate ring, so as to secure a more uniform heating throughout the entire mold.

To this end, I may run a steam pipe 17 through the outer portion of the intermediate 85 ring, and a similar pipe 18 around the inner portion of the intermediate ring. Steam is admitted at one point to this pipe, and flows around it, and thence outwardly, as by means of the connections shown. The intake and 90 outlet ends of the pipe can be taken care of through the central open part of the mold.

As a modification, I may make the central member of two counter-part right and left hand portions 9^a, spaced apart by means of 95 two rings 19 and 20 to provide a space 21 through which steam may be caused to flow. The rings 20 and 19, in such case, would preferably be welded to the portions 9^a.

What I claim is:—

1. A double tire vulcanizer mold composed of two outer half ring members and an intermediate ring member complementary to the outer ring members and having an inner, annular flange constituting a thin, common wall 105 for the two mold cavities, together with a steam passage in the intermediate member adjacent its periphery and a second steam

passage in said intermediate member adjacent its inner edge.

2. A double tire vulcanizer mold comprising two outer half ring members each having 5 a mold, cavity, and an intermediate ring member, said intermediate ring member having an inner, annular flange having on its opposite faces mold cavities complementary to

the cavities of the outer rings, a steam passage adjacent its periphery, a steam passage 10 adjacent its inner edge and a relatively thin wall between its mold cavities.

In testimony whereof, I have hereunto signed my name.

CLAUDE A. WITTER.
